UNITED STATES PATENT OFFICE.

ALONZO F. OLDS; OF NEW YORK, N. Y., ASSIGNOR OF ONE-HALF TO
CHARLES H. PHELPS, OF FAIRFIELD, CONNECTICUT.

GAS-REGULATOR.

SPECIFICATION forming part of Letters Patent No. 340,454, dated April 20, 1886.

Application filed January 26, 1886. Serial No. 189,853. (No model.)

To all whom it may concern:

Be it known that I, ALONZO F. OLDS, of New York, in the county of New York and State of New York, have invented certain new and useful Improvements in Gas-Regulators; and I do hereby declare that the following is a full, clear, and exact description thereof, reference being had to the accompanying drawings, making part of this application.

10 My invention relates to certain new and useful improvements in gas-regulators, and has for its main object to provide for use a contrivance by means of which the gas-consumer may be able to use the gas usually supplied 15 under a uniform pressure, so as to produce a perfectly steady light at the burner, and with the minimum degree of pressure necessary to produce perfect combustion and develop the best eliminating results without any waste of 20 the gas, and which contrivance at the same time shall be simple, durable, and efficient in its operations, and not liable to derangement in its working parts; and to these main ends and objects my invention may be said to consist, 25 primarily, in the use in a single regulator contrivance of two independently-operating regulating-valves, one operated by the pressure of the gas within the regulator upon a reservoir of glycerine or other suitable liquid and a 30 float immersed therein, and the other actuated through the medium of a flexible diaphragm acted upon by the gas-pressure, all as will be hereinafter more fully explained; and, secondarily, in the use, in connection with a gas-regulator, of reflecting shields or arresters, against 35 the surface of which the inflowing gas supplied to the regulator from the usual meter impinges, and which serve to arrest and eliminate from the gas most, or all, of the tar contained 40 therein, thus permitting the gas to pass through the regulators and to the burner in a condition to produce better results, and at the same time preventing any fouling or clogging of the valvular devices of the regulator 45 by the deposits on any of the surfaces thereof of such tarry ingredients as are usually found in the ordinary coal-gas.

To enable those skilled in the art to which my invention relates to make and use the 50 same, I will now proceed to more fully de-

scribe the construction and operation of a contrivance made according to my invention, referring by letters of reference to the accompanying drawings, which form a part of this specification, and in which I have shown my 55 invention carried out in that form in which I have so far successfully practiced it.

In the drawings, Figure 1 is a top view of a gas-regulator made according to my invention. Fig. 2 is a vertical section of the same, taken 60 at the line *x x* of Fig. 1. Fig. 3 is a partial duplicate of Fig. 2, but showing the valves in different positions. Fig. 4 is a detailed sectional view (on an enlarged scale) illustrating a device to be presently explained. 65

In the several figures the same part will be found designated by the same letter of reference.

A is the main body or case of a gas-regulator, which is about cylindrical in form, as 70 shown, and which is provided at its bottom with a centrally-arranged upwardly-projecting tube, B, and with an auxiliary chamber, C, with the central bottom opening of which latter is connected the ascending leg or portion 75 of an ordinary pipe, D, which is supposed to extend thence to the gas-meter.

Over the upper open end of the tubular case A is arranged a covering or casting, E, which is securely bolted to the flange at the upper 80 end of A, as shown, and which is formed with a laterally-projecting portion, E², and with a centrally-arranged upwardly-projecting and perforated portion, J, in which latter is formed, as will be presently explained, a seat for one 85 of the regulator-valves.

L is a dome-shaped top or cover to the regulator, which at its perimeter is securely bolted, as shown, to the upper flanged edge of part E, and which is formed with an extension, which 90 also covers over the laterally-projecting portion E². This cover L is formed or provided with a central opening having a screw plug or stopper, j, which is suitably perforated to permit a free ingress and egress of atmospheric 95 air to and from the interior of the dome. Said dome or cover L is also formed with an upwardly-projecting pipe-joint, n, into which is secured the lower end of a suitable tube or pipe, N, which is supposed to pass thence to 100

the pipes and burners of the dwelling or apartment to be supplied with gas through the regulator, and between the coupled perimeters of said device L and the casting E is securely clamped the perimeter of a flexible diaphragm, (preferably composed of leather,) M, to the center of which is secured, by means of suitable clamping-disks, the stem l of the valve K.

From the under surface of the casting E there depends a hollow cylinder or tube, e, the lower end of which is located, as shown, slightly above the bottom surface of the main case A of the regulator, and within the lower portion of this cylindrical device e is located and works the annular hollow float F, which, by means of upwardly-branching arms f, supports the hollow check-valve G. The upwardly-projecting and hollow stem-like portion H, which is formed or provided with a depending tubular flange, g, is arranged in and works up and down within (during the movements of the valve G) an annular cup-like receptacle, h, which is formed at the lower portion of the tubular device I, and in which is kept a suitable supply of glycerine to form a seal or packing, and also to act as a lubricator to the parts having relative motion, the said device I being securely held in place concentrically with the valve-stem H by means of arms or brackets i, depending from the casting E and securely fastened at their lower ends to said device I. The upper end of the tube B is beveled inwardly and downwardly, as clearly shown, to form a perfect seat for the valve G, which rests upon said tube when in its lowest position or closed, while the valve K, which is connected, as before mentioned, with the diaphragm M, closes upwardly against the tapering seat formed, as shown, in the device marked J.

The tubular device J is preferably made, as shown, with its closed upper end or head depressed to the proper extent and in the proper shape to form a seat or support for the convex bottom of the valve K, whenever the latter may be permitted to descend and rest by gravity upon said device.

m is a filling and vent tube, which is provided with a suitable screw-cap, m², and which has two or more holes, p, (see Fig. 4,) near its upper end and located at different elevations, for a purpose to be presently explained; and O is another tube provided with a suitable cap or screw-cover, and also with a stop cock or key, s, which tube and cock constitute the usual means by which a pressure-gage may be applied to the regulator for the purposes of testing the gas-pressure therein, and adjusting or setting the parts of the regulator for proper operation.

b and c are respectively an inverted-dish-shaped solid and a similar dish-shaped perforated receptacle or arresters for receiving upon their surface and discharging therefrom onto the bottom of the auxiliary chamber C, and in a liquid condition, the tarry ingredient contained in the supply of gas which comes from

the gas-meter to the regulator. These deflectors b and c are arranged, by preference, in the manner shown, the lower one being supported or held in place by suitable arms, v, extending upwardly from the coupling a of the chamber C, while the upper one, b, is supported by posts u, connecting it with the other one. Both the shapes and the arrangement, as well as the mode of supporting these deflectors or tarry arresters, may of course be varied without departing from the spirit of my invention.

The bottom of the chamber C is preferably made in the form of an annular dish, for the purpose of more efficiently collecting and concentrating the liquid tarry matter which drips from the deflectors or arresters b and c, and to permit the ready discharge of any accumulation through an exit-hole provided (in the case shown) with a screw stopper or plug, d. The lower portion of the case A is supplied and is kept supplied with the proper quantity of a suitable liquid material, preferably glycerine, for the purpose of properly supporting and acting upon the annular float F, in a manner well understood.

At Fig. 2 the arrows indicate the directions in which the supply of gas enters from the pipe D, passes through the valve and other portions of the regulator, and makes its exit into and through the pipe N, which is supposed to supply the gas-burners to be regulated. The broken lines in said figure illustrate the supplies of glycerine both in the lower portion of the main case A and in the cup-like device h, and in this figure the contrivance is illustrated as it would appear with reference to the relative positions of its working parts when in operation, regulating the gas supplied to the burners in use, while at Fig. 3 the valves G and K are represented as both closed, as they would be only whenever the burners might all be shut off and the supply from the gas-main exercising its full or undiminished pressure within the case A.

In the operation of my improved regulator the gas supplied through the pipe D comes first into contact with the lower surfaces of the tarry arresters b and c, and is by them deflected in two currents laterally, as illustrated, by which deflective action of the inflowing gas the said devices b and c receive as a sort of deposit on their under surfaces a certain quantity of tarry liquid matter which would otherwise pass on and upwardly through the valvular devices of the contrivance or machine, and thence partially to the gas-pipes and burners. The arrest or elimination of this ingredient of the gas in the simple manner shown I consider to be an important and novel feature of my improved machine, since thereby I am enabled not only to prevent fouling of the valvular and other working parts of the machine, but also effect the final discharge of the gas for consumption in a better condition for illuminating purposes. As the gas passes upwardly through the tube B, and thence out beneath the open valve G, it fills the interior of the tubular

chamber formed by the depending cylinder *e*, exteriorly of the device *I*, and escapes between the top of the valve *K* and its seat into the chamber or space comprised between the casting *E* of the regulator and the lower surface of the flexible diaphragm *M*, from which space the gas flows into the supply-pipe *N*, leading to the burners.

In adjusting or setting the machine for operation or use, the supply of glycerine and the condition of the float *F* should be such, relatively to the initial gas-pressure in the machine, as to cause the valve *G* to permit the escape through it of the gas at about a pressure of seven-tenths of an inch by the gage, while the adjustment of the valve *K* (by weighting the diaphragm in the usual manner) should be such as to permit the escape through this valve at a pressure, say, about five-tenths of an inch, thus producing the relationship of about seven to five in the pressures at the localities of the two valves, which relative pressures I have found to produce the most desirable results and practically a perfect regulation of the flow of gas to the burners supplied, so as to produce a perfectly steady light, with the minimum degree of gas necessary to perfect combustion and illumination.

By the use of the two independently operating valvular devices, substantially as shown and described, I produce for use, it will be seen, a duplex regulator, in which, while each of the valves works independently of the other, and is in itself, to a certain extent, a complete regulator, the two regulators, so to speak, effect a sort of compensation for any fluctuation or irregularity in the pressure of the gas supplied to the machine, and thus I am able to produce results which would be impossible of accomplishment in any regulator containing only a single valvular means of regulation. It will be seen that just in proportion as the valve *G* may rise to permit an increased flow or passage of gas will the increased supply of gas therefrom admitted to the interior of the cylinder *e* (and thence to the diaphragm *M*) immediately operate to partially close the valve *K*, thus preventing the escape through the burners of the surplus supply which entered beneath the valve *G*, and vice versa. Therefore, as experience has demonstrated in the practical operation of my invention, a gas regulator or governor made as shown and described, with a duplex or double valvular mechanism, in which each valve operates independently of and counter to the other, will effect a perfect uniformity at a fixed standard of pressure in the supply of gas to the burners connected

with such governor irrespective of any fluctuations of pressure which may occur in the gas main or supply from the meter.

Of course many changes and modifications, both in the form and in the arrangements of the devices shown and described, may be made without departing from the spirit of my invention, so long as the novel principle of construction and mode of operation described be retained, the gist of my invention consisting, as I have explained, first, in a gas regulator or governor provided, as shown, with two independently-operating valves or checks acting counter to each other and in a compensatory manner; and, second, in the use or employment of any suitably shaped and arranged deflectors, against which the current of inflowing gas from the supply-pipe must impinge, and by which said current will be bodily deflected in substantially the manner and for the purposes explained.

Having now so fully explained my invention and the best mode now known to me of carrying out the same, what I claim as new, and desire to secure by Letters Patent, is—

1. In a gas regulator or governor, the combination of two valvular devices or mechanisms acting independently of each other and in a compensatory manner, as shown and described, and operated upon respectively by the pressure of gas in the supply-main and by the reduced pressure of gas within the main chamber of the regulator, so that in proportion as the valve first acted upon by the incoming gas will be opened will the valve through which the gas has next to pass be closed by the increased pressure within the chamber of the regulator, all substantially as and for the purposes hereinbefore set forth.

2. In a gas regulator or governor, the combination, with the gas-induction passage, the gas-eduction passage, and the main chamber of the regulator, of one or more deflectors arranged or located between the gas-induction passage and the main chamber of the regulator, and operating, as described, to arrest or deprive the inflowing gas of its tarry ingredients and cause the same to collect in a suitable receptacle beneath the arresting devices, from which chamber such matter may be drawn off from the regulator, as set forth.

In witness whereof I have hereunto set my hand this 23d day of January, 1886.

ALONZO F. OLDS.

In presence of—

A. M. WILLIAMSON,
HERMAN HANSEN.
